TRAIN CONTROL

Filed Nov. 20, 1924

FIG. 1.

FIG. 2.

INVENTOR.
W. W. Wenholz
BY Neil C. Preston,
his ATTORNEY

UNITED STATES PATENT OFFICE.

WALTER W. WENHOLZ, OF ROCHESTER, NEW YORK, ASSIGNOR TO GENERAL RAILWAY SIGNAL COMPANY, OF ROCHESTER, NEW YORK.

TRAIN CONTROL.

Application filed November 20, 1924. Serial No. 751,061.

This invention relates to automatic train control systems, and more particularly to the trackway equipment of a train control system of the well known continuous inductive type.

In block signal systems, it is sometimes necessary to divide a block, that is, that portion of track on any part of which the presence of a train produces the same controlling effect on the block signals, into two separate isolated track circuit sections. For example, in the type of block signaling system for single track railroads, commonly known as the absolute-permissive-block system, one form of which is disclosed in the patent to Wight, No. 1,294,736, dated Feb. 18, 1919, it is necessary to have the block between opposing signals, particularly adjacent to the sidings, divided into two separate track circuit sections, each having a track relay, in order that the track relays may be operated sequentially during the passage of trains in opposite directions. Also, on double track railroads, on account of the length of the block, ballast conditions, or other practical considerations, it is sometimes necessary to divide the block into two separate track circuit sections.

In applying continuous inductive train control to such divided blocks or cut-sections, it is desirable to supply the train control circuit throughout the length of the block and control it from one point. In other words, it is desirable to make the track rails of the block continuous with respect to the alternating train control current, while separate or isolated for the direct current of the track circuits so that either the track phase of a continuous inductive control system, or both the track phase and line phase of such system may be supplied throughout the length of the block and conveniently controlled at one point.

The principal object of the present invention is to provide an arrangement of devices and circuits which will enable the train control current to be supplied throughout the length of the block, while the direct track circuit current is confined to the separate track circuit sections of the block.

In describing the invention in detail reference will be made to the accompanying drawings in which:

Fig. 1 shows conventionally a block of an

automatic block signal system composed of two sections divided by insulating joints, having train control apparatus superimposed thereon embodying the present invention; and

Fig. 2 shows a junction point of the two sections of a block in a similar system in which only one of the rails is insulated, and having a modified form of train control apparatus associated therewith.

Referring to Fig. 1, to simplify and facilitate the explanation of the nature of the invention, there has been illustrated an embodiment of the invention applied to a block of a double track railroad which is divided into two separate direct current track circuit sections. For simplicity, Fig. 1 merely shows provision for supplying a track phase, track circuit, or loop circuit current for the train control system, that is, alternating current flowing down one track rail and back the other at any given instant; but it should be understood that the usual type of 3-position continuous inductive type of system, employing the line phase current as well as a track phase current, may be used in connection with the invention. The car apparatus of the train control system, which may take any one of the well known or suitable forms has not been shown.

In Fig. 1 there has been illustrated a block I, with the adjacent ends of two other blocks H and J. For simplicity, it is assumed that all blocks will be equipped the same, so that a description of one will suffice for all; and for convenience, the same reference characters with distinctive exponents are used for corresponding parts and circuits associated with the different blocks. Using the reference characters for the block I, the usual track rails 1 are provided with insulated joints 2 defining the ends of this block, traffic being from left to right, as indicated by the arrow.

The block I is divided into two track circuit sections I¹ and I² by a pair of insulated joints 3. At the entrance end of the first or rear section I¹ is a track relay 4 connected across the track rails in the usual manner. The track relay 5 for the second or forward section I² is connected across the track rails at the exit end thereof. At the exit end of the first section I¹ is a track battery 6 which is connected by wires 7 and 9 and an inductive reactance or impedance 8 across the track rails

at the exit end of this section; and a track battery 10 is connected across the track rails at the entrance end of the second section I^2 by wires 11 and 12 and said inductive reactance 8 in a similar manner. The inductive reactance or impedance 8 has a resistance corresponding to the usual limiting resistance connected in series with track batteries; and if desired, an external adjustable resistance may be used in series with the track battery either separately or in their common connection. This impedance is made sufficiently high so as to maintain an inter-rail potential for the alternating train control current, to assure that a train entering the block, with its wheels and axles in multiple with this impedance, will receive enough current to cause satisfactory operation of its car relay.

Train control current is supplied across the exit end of the block by a transformer 14, the secondary of which is connected across the track rails 1, in series with a resistance or impedance 15. This resistance, together with the internal resistance of the secondary, is made high enough so as not to shunt out the direct track circuit current from the track relay 5, or interfere with the proper operation of this track relay. This resistance 15, is ordinarily made largely, if not wholly, non-inductive, but may have as much inductive reactance as may be required under some conditions to obtain phase displacement. The primary of the transformer is energized from the usual transmission line 16 and has its circuit opened and closed in accordance with traffic conditions in the next block in advance. In the arrangement shown, the circuit of the primary of this transformer includes the front contact of a line relay HR^1 which has an energizing circuit passing through the front contacts of the two track relays of the next block in advance. This line relay also serves to control the indication of the wayside block signal Z , which may be of the semaphore type, as shown, or of any other suitable type, together with suitable provisions for obtaining the three indications of stop, caution and proceed; approach lighting, if color light signals are used; and other expedients, all in accordance with the knowledge and teachings of the art.

It will be evident that the direct track circuit current is confined to each track circuit section, excepting leakage through the ground. The track batteries are preferably connected to oppose each other, as shown, this serving to reduce the potentials to ground and also the direct current voltage in the conducting path through which the alternating train control current flows. Train control current flows through the length of the block in the following circuit:—Beginning at the secondary of transformer 14, impedance 15, rail 1, wires 12 and 7, battery 6, rail 1, track relay 4 (or the wheels and axles of a train),

rail 1, wires 9 and 11, battery 10, rail 1 back to the secondary of transformer 14. This current is cut off the block if the next block in advance is occupied, thereby producing the caution or stop indication in the 2-position type 70 of continuous inductive system. A train in the first or rear section deprives the following train in that section of train control current by the shunting action of its wheels and axles; and similarly, a train in the second or forward 75 sections shunts out the train control current from the first or rear section. A train entering an occupied block does not receive train control current even though that current is supplied to the track rails of that block because the next block in advance is not occupied.

Fig. 2 shows a modified arrangement, using one insulated joint 3^a between the track circuit sections of the block. The track batteries 6^a and 10^a are connected by wires 11^a and 7^a in series around this joint in opposition; and the impedance 8^a is connected from the other rail to the wires between the batteries, as shown. It will be evident that the insulated joint 3^a isolates the two track sections so far as the direct track circuit current is concerned; but the alternating current flows down one rail without opposition and down the other rail around the joint 3^a through 90 the two batteries 6^a and 10^a and wires 11^a and 7^a in series.

Having thus shown and described in a rather specific manner two rather specific embodiments of the present invention, it is desired to be understood that the particular arrangements illustrated have been selected so as to facilitate the description of the invention rather than to show the scope thereof, and that various changes, modifications and additions may be made to adapt the invention to single track signaling systems, such as the well known absolute permissive block system, isolated track sections for crossing signals, or the like, without departing from the scope of the invention or the idea of means underlying the same.

What it is desired to secure by Letters Patent of the United States is:—

1. Trackway apparatus for a train control system employing direct current and alternating current comprising, an insulated section of the track rails, means for independently impressing a direct current potential across two portions of said section of the track rails, and for impressing alternating current potential across the entire section of the track rails.

2. In an automatic train control system; in combination trackway apparatus for wayside signal and train control purposes comprising; a section of track rails divided into two portions by insulating joints, means for impressing an alternating current potential for train control purposes across one end of 130

- said section, and means bridging said insulated joints for conducting said alternating control current through the entire length of said section and for independently impressing direct current potentials for wayside signal control purposes across the said two insulated portions of said section. 5
3. Trackway apparatus for automatic train control systems comprising, a section 10 of the track rails divided into two portions by insulating joints, partial circuits each including a source of energy connected across the track rails on each side of said insulating joints, an inductive reactance common to said 15 partial circuits, whereby current from said sources of energy may flow independently in said two portions of the track rails and a distinctive alternating current may flow in the rails of the entire section. 20
4. Trackway apparatus for automatic train control systems comprising; a section of trackway divided into two portions by insulating joints; a track wayside signal controlling circuit for one of said portions including a track relay, the two track rails of said portion, a track battery and a reactance coil in series; a track circuit for wayside signal control purposes for the other of said portions including a second track relay, the 25 two track rails of said other portion, a second track battery and said reactance coil in series; and a track circuit for train control purposes including the track rails of the entire section and the track batteries of the 30 said two portions in series. 35
5. Trackway apparatus for automatic train control systems, comprising, two successive direct current track circuits for wayside signal control purposes each comprising 40 insulated portions of the two track rails connected in series through a common portion including a reactance coil, and an alternating current track circuit for train control purposes superimposed on said direct current track circuits including the track rails of said two direct current track circuits, said reactance coil preventing the flow of alternating current from one rail to the other at the junction of said two direct current track 45 circuits. 50
6. Trackway apparatus for automatic train control systems comprising; a track portion divided by insulating joints into two sections, a track relay at each end of said 55 track portion, a source of energy bridged across the rails of each of said sections adjacent said insulating joints, another and distinctive source of energy bridged across one end of said track portion and 60 having in series therewith a device for limiting the flow of current of the character derived from the first mentioned sources of current, and means permitting the flow of current from said distinctive source down one 65 rail of said two sections and back through
- the other and preventing the flow of current from one rail to the other at the junction of said sections. 70
7. Trackway apparatus for automatic train control systems comprising, a track section, a relay at each end of said track section, a source of current of a particular character bridged across the rails at one end of said track section, and means including another source of current and a device permitting the flow of current from said another source but not permitting the ready flow of current of said particular character connected in series and bridged across the rails at an intermediate point. 75
8. Trackway apparatus for automatic train control systems comprising, a track section, a relay at each end of said track section, a source of current for each of said relays bridged across the rails at an intermediate 80 point in said section, another source of current distinctive in character bridged across the rails at one end of said section, and means for preventing current from said another source from flowing from one rail to the other 85 at said intermediate point. 90
9. Trackway apparatus for automatic train control systems, comprising, a section of track divided from the rest of the trackway by insulating joints, a source of alternating current bridged across the rails at one 95 end of said section, a battery having an inductive reactance in series therewith connected across the rails of said section at an intermediate point, whereby due to the impedance of said inductive reactance to the flow of alternating current the source of alternating current is not shunted by said battery and the alternating current potential is applied across the rails throughout the entire section. 100
10. Trackway apparatus for automatic train control systems, comprising, a track portion divided by insulating joints into two sections, a track relay for each end of said track portion, a source of energy bridged across the rails of each of said sections adjacent said insulating joints, another and distinctive source of energy of a different kind bridged across one end of said track portion 110 and having in series therewith a device for limiting the flow of current of the kind derived from the first mentioned source of current, and means interconnecting the two rails and permitting the flow of current from said distinctive source down one rail of said two sections and back through the other and preventing the flow of current from one rail to the other at the junction of said sections. 115
11. Trackway apparatus for train control 120 systems, comprising, a stretch of track divided by insulating joints into two insulated sections, means bridging each insulating joint and including a track battery, an inductance connected between the two 125 130

bridging means, and a source of alternating current connected to the rails at one end of said stretch of track.

12. Trackway apparatus for train control systems, comprising a stretch of track divided by insulating joints into two insulated sections, means bridging each insulating joint and including a track battery, an inductance connected between the two bridging means, said track batteries being con-

nected in opposition to each other through the inductance, a source of alternating current connected across the rails at one end of said stretch of track, a current limiting resistance in series to the rails with the alternating current source, and a direct current track relay at each end of the stretch of track.

In testimony whereof I affix my signature.

WALTER W. WENHOLZ.
